UNITED STATES PATENT OFFICE.

ALEXANDER M. GOW, OF DULUTH, MINNESOTA; AMERICAN EXCHANGE NATIONAL BANK OF DULUTH EXECUTOR OF SAID ALEXANDER M. GOW, DECEASED.

AGITATION SEPARATOR.

Application filed November 17, 1920. Serial No. 424,777.

To all whom it may concern:

Be it known that I, ALEXANDER M. Gow, a citizen of the United States, residing at Duluth, in the county of St. Louis and State of Minnesota, have invented certain new and useful Improvements in Agitation Separators, of which the following is a specification.

My invention comprises means whereby material composed of small particles may be subjected to agitation to facilitate the separation from each other of particles of differing characteristics. The means is adapted to be used in connection with material wherein the particles may differ in size, shape, specific gravity or magnetic permeability and is adapted to effect the separation of unlike particles. In securing such separation it is highly desirable that a mass or layer of the material be shaken or agitated. This idea of agitation has been heretofore used in a large number of devices, particularly in those used for concentration of ore. My apparatus is particularly well adapted for such use, but I do not desire to limit its application to such material as ores as it is obviously adapted broadly for use in producing agitation among particles of any mass of material for any purpose, as well as for use in separators adapted to separate material of various kinds.

I have found in the use of electro-magnets energized by alternating currents, that if a sheet of steel be movably supported within the magnetic field, the fluctuation in the strength of that field will cause the sheet of steel to vibrate and that this vibration may be varied in rapidity by a change in frequency of the alterations and in intensity by variation in the strength of the magnetic field. If upon such a sheet of steel particles of material are placed, they will respond to the vibration and will be thrown into a state of intense agitation and, if a thin stream of water be allowed to flow over the sheet, the water may be agitated to such an extent that drops are thrown upward from the surface. By the use of this electro-magnetic means the frequency of vibration may be varied within wide limits and the intensity of vibration may also be greatly varied. In the use of mechanical means such as cams, knockers, shakers, or other devices of like character for producing vibration or agitation the intensity and

rapidity of vibration are greatly limited for mechanical reasons and the parts undergo such strains as to be very subject to wear and breakage.

It is an object of the present invention to provide means adapted to separate material comprising particles of varying characteristics and to accomplish that separation with great rapidity and ease of operation. It is also an object to provide means of the character described which is subject to ready adjustment in its operation through variation in rapidity and intensity of the vibration. It is an additional object to provide a device which is relatively simple in construction, durable in use, and relatively inexpensive of installation. Other and further objects will appear as the description proceeds.

I have illustrated certain preferred embodiments of my invention in the accompanying drawings in which—

Figure 1 is a diagrammatic view illustrating one form of my device;

Figure 2 shows a somewhat modified form of the device of Figure 1;

Figure 3 shows a form of device utilizing belt conveyers;

Figure 4 is a cross section of the form of the device shown in Figure 3; and,

Figure 5 shows a modified form using an exhaust blower.

In Figure 1 the variable speed motor 7 is shown directly connected to an alternating current dynamo 8. The circuit from the dynamo includes the electro-magnet 9 and the rheostat 10. The steel plate 11 is resiliently supported by the springs 12 upon the columns 13, the plate being located above the magnet 9.

In Figure 2 a plate 14 formed with a plurality of transverse corrugations is supported upon the columns 15 and springs 16, the plate being tilted to slope both transversely and longitudinally. The hopper 17 is shown adjacent the upper most corner of plate 14 and the electro-magnet 18 is shown adjacent the center of the underside of the plate.

In Figure 3 the belt conveyer 20 is carried by the rollers 21 and 22. The plate 23 is located adjacent the underside of the upper portion of the belt, the plate being supported by the spring 24 from the electro-magnet 25. The hopper 26 is placed adjacent the point where the upper portion of

the belt starts its movement. As best shown in Figure 4, the second conveyer belt 28 is carried by the rollers 29 and 30, the lower travel of the belt being adjacent the upper surface of the belt 20. The electro-magnets 31 and 32 are placed near the upper side of the lower portion of the belt 28. The receiving hopper 33 is located at the right side of the belt 20.

10 In Figure 5 the plate 34 is supported from the springs 35 and columns 36, the plate sloping downwardly to the right. The feed hopper 37 is located adjacent the upper end of the plate, and the discharge hopper 38 below the low end of the plate. The electro-magnet 39 is located under the central portion of the plate 34 and a rotary exhaust fan 40 has its intake 41 located above the central portion of the plate 34 20 and thus above the electro-magnet 39.

In the form of the device shown in Figure 1 the frequency of the alternations in the current supplied to the magnet 9 is varied by changing the speed of the motor 7 which 25 consequently varies the speed of the dynamo 8. The intensity of the magnetic field is varied by means of the rheostat 10 which varies the amount of current passing from the dynamo to the magnet.

30 I have shown the plate 11 as supported upon springs 12. I have found, however, in practice that any thin sheet of steel, even if rigidly held at its corners, will have enough elasticity and freedom of movement 35 to be thrown into a state of intense vibration by a properly placed and proportioned electro-magnet or series of such magnets. Consequently the springs 12 are not essential although their use may be desirable to increase the intensity of the vibration with a given magnetic force.

If the layer of comminuted material or material composed of small particles be placed on the plate 11 and the magnet 9 be 45 energized, the vibration of the plate will cause movement of the particles. This movement may create stratification of the particles according to their physical characteristics, or the frequency and amplitude 50 of the vibrations may be such that the particular material is simply kept in a state of intense vibration.

In the form of the device shown in Figure 2 material is passed from the hopper 17 55 to the upper corner of plate 14. In the use of a plate of this character placed within the magnetic field and sloping in two directions, parallel to the line of corrugations or ripples, and at right angles thereto, a marked 60 separation of the material occurs. The lighter particles tend to gather at the bottom of the grooves and to flow lengthwise of the grooves, while the heavier particles will tend to flow over the tops of the corrugations 65 and thus to move from riffle to riffle and in a

direction longitudinally of the plate. This action may be further facilitated when handling certain kinds of material by causing a film of water to flow across the table. In certain forms of concentrating machinery now in use, a table having ripples is supplied with fine material and water and is placed upon an incline and caused to shake backwardly and forwardly, this action causing the heads to travel in the direction of the ripples and the heads to separate therefrom. In the application of my invention to tables of this general character I cause the table to vibrate in a substantially vertical direction by means of magnets placed below the table. The amplitude of the vibration would be slight and the rapidity very high, their exact adjustment depending somewhat upon the nature of the material, but in any case it gives the particles a much better opportunity to flow and to separate than they have with the present to and fro moving tables.

In Figures 3 and 4 is shown a form of apparatus wherein the material to be separated is not carried directly by a vibrating plate. The material is carried upon the belt conveyer 20 which is preferably formed of non-magnetic material, the belt being carried for a portion of its travel in contact with the vibrating plate 23. The vibration of the plate is thus transmitted to the particles as they are carried past the plate upon the conveyer. This form of the device is of course susceptible to use in connection with any form of separation which is facilitated by agitation. In the particular form shown in the figures I have shown it in connection with a device adapted for the separation of magnetic metallic ores or for the separation of material of varying magnetic permeability. The second belt 28 travels at right angles across the path of the belt 20 adjacent the vibrating portion of that belt. The series of electro-magnets 31 and 32 are placed above the lower portion of the belt 28 and serve to attract the metallic particles contained in the comminuted or pulverized ore passing on the belt 20. These metallic particles are held by the magnets 31 and 32 in contact with the belt 28 and are thus carried by the movement of the belt and dropped into the hopper 33 at the end of the magnetic field created by the series of magnets. The attraction of the metallic particles by the magnets 31 and 32 is very greatly facilitated by the vibration set up in the particles by the movement of the plate 23.

In the form of the device shown in Figure 5, the material drops from the hopper 37 and passes down the slope of the plate 34 due to gravity and assisted by the vibration caused by the magnet 39. The exhaust intake 41 located adjacent the portion of most intense vibration draws off the

lighter particles, while the heavier particles pass downward and are deposited in the hopper 38. Obviously the exhaust if made sufficiently strong will draw off all of the material. By careful adjustment of the amplitude and rapidity of the vibration and of the strength of the exhaust, practically any desired separation may be effected.

It is to be understood that all of the showings in the drawings are diagrammatic in character and that the number of magnets and their sizes may be varied as may also the mechanical details of the supports of the various members, and of the conveyers and their associated parts.

While I have described more or less precisely the details of construction of my invention, I do not wish to be understood as limiting myself thereto, as I contemplate changes in form and the proportion of parts and substitution of equivalents as circumstances may suggest or render expedient, without departing from the spirit of my invention. For example, instead of an alternating current, an interrupted or fluctuating direct current may be used to energize the magnets.

I claim:

1. Separation apparatus comprising a plate, means located adjacent one face of the plate adapted to produce a magnetic field, and means adapted to fluctuate the strength of the field, the variation in strength serving to vibrate the plate and a conveyer adapted to move in contact with the plate, the conveyer being adapted to carry the material to be separated.

2. Separation apparatus comprising a plate, means located adjacent one face of the plate adapted to produce a magnetic field, and means adapted to fluctuate the strength of the field, the variation in strength serving to vibrate the plate, and a non-magnetic conveyer belt adapted to move in contact with the plate, the conveyer being adapted to carry the material to be separated.

3. Separation apparatus comprising a conveyer adapted to carry the material to be separated, a plate located in contact with a portion of the conveyer, and means adapted to vibrate the plate, a second conveyer traveling adjacent the first conveyer and means adapted to selectively transfer material from the first to the second conveyer.

4. Separation apparatus comprising a conveyer adapted to carry material to be separated, a plate located in contact with a portion of the conveyer, means located adjacent the plate adapted to produce a

magnetic field, means adapted to fluctuate the strength of the field, the fluctuation in strength serving to vibrate the plate and thereby to vibrate the conveyer, a second conveyer traveling adjacent the first conveyer and means adapted to selectively transfer material from the first to the second conveyer.

5. Separation apparatus comprising a conveyer adapted to carry the material to be separated, a plate located in contact with a portion of the conveyer, means located adjacent the plate adapted to produce a magnetic field, means adapted to fluctuate the strength of the field, the fluctuation in strength serving to vibrate the plate and thereby to vibrate the conveyer, a second conveyer traveling adjacent the first conveyer and magnetic means located adjacent the second conveyer adapted to selectively transfer material from the first to the second conveyer.

6. Separation apparatus comprising a conveyer adapted to carry material to be separated, a plate located in contact with a portion of the conveyer, means located adjacent the plate adapted to produce a magnetic field, means adapted to fluctuate the strength of the field, the fluctuation in strength serving to vibrate the plate and thereby to vibrate the conveyer, and means adapted to vary the rapidity and the amplitude of the fluctuations, a second conveyer traveling adjacent the first conveyer and means adapted to selectively transfer material from the first to the second conveyer.

7. Separator apparatus comprising a non-magnetic belt conveyer adapted to carry the material to be separated, a plate located in contact with the under side of a portion of the conveyer, electro-magnetic means located adjacent the plate, means adapted to fluctuate the strength of the magnetic means, the fluctuations serving to vibrate the plate and thereby to vibrate the conveyer and the material thereon, a second conveyer traveling in spaced relation to the upper face of the first conveyer, electro-magnetic means located above a portion of the second conveyer and adapted to attract magnetic particles from the material upon the first conveyer, and a receiving hopper located adjacent the end of the magnetic field of the upper conveyer and adapted to receive material released therefrom.

I signed at Duluth, Minnesota, this 11th day of November, 1920.

ALEXANDER M. GOW.
